UNITED STATES PATENT OFFICE.

EDWARD MASLICH, OF ST. JOSEPH, MICHIGAN.

MACHINE FOR LOADING TRANSFERS FOR KNITTING MACHINERY.

1,195,833.

Specification of Letters Patent. Patented Aug. 22, 1916.

Application filed March 19, 1909. Serial No. 484,577.

To all whom it may concern:

Be it known that I, EDWARD MASLICH, a subject of the Emperor of Russia, and resident of St. Joseph, Berrien county, Michigan, have invented a certain new and useful Improvement in Machines for Loading Transfers for Knitting Machinery, of which the following is a specification.

In the manufacture of hosiery, it has been the practice to knit the tops separately, and to then transfer the same to knitting machines. These tops are made by knitting a continuous tube of ribbed fabric, and by then cutting the same into lengths suitable for the purpose. In order to transfer a top to a knitting machine, it was necessary to place the top on a transfer, and to then, in the well known manner, transfer the top to the needles of the knitting machine. It was necessary to place the loops of the raw edge of the top on the quills or points of the transfer by hand, or by mechanism of some kind. The transfer is ordinarily a ring with quills or points set around in a circular row thereon. Each quill or point receives a loop on the edge of the top, and thus the loops of the top are placed in condition to be readily transferred to the needles of the knitting machine. Then the foot is knitted in continuation of the top, in the ordinary manner. The loading of the transfers by hand was slow and laborious, especially in the case of silk or other finely knit hosiery. The mechanism proposed for the purpose does not stretch out the top or web by moving the transfer backward. Each loop of the yarn had to be placed by hand on a quill or point of the transfer, and this took considerable time, as it was necessary to do this by means of devices which did not employ the principles best calculated to insure good results.

My invention contemplates, therefore, a machine for automatically loading transfers, by placing the loops of the yarn on the edge of the top on the quills or points of the transfers, in the machine which moves the transfer back and forth to receive and stretch out a length of the web, and for automatically cutting off the top from the tube of knitted fabric, when the transfer reaches the limit of its backward travel, thus saving time and labor, and reducing the cost of hosiery of this character.

call cutting off the top from the tube of knitted fabric, when the transfer reaches the limit of its backward travel, thus saving time and labor, and reducing the cost of hosiery of this character.

In the accompanying drawings—Figure 1 is a side elevation of a machine for loading transfers for knitting machines, embodying the principles of my invention. Fig. 2 is a transverse section, on a larger scale, on line 2—2 in Fig. 1. Fig. 3 is a similar section on line 3—3 in Fig. 1. Fig. 4 is a similar section on line 4—4 in Fig. 1. Fig. 5 is a similar section on line 5—5 in Fig. 1. Fig. 6 is a similar section on line 6—6 in Fig. 1. Fig. 7 is a similar section on line 7—7 in Fig. 1. Fig. 8 is a vertical longitudinal section on line 8—8 in Fig. 5. Fig. 9 is a transverse section on line 9—9 in Fig. 8. Fig. 10 is a section on line 10—10 in Fig. 9. Fig. 11 is a front elevation of the cutter head—that is, the knives for cutting off the top after a sufficient length of the tubular fabric has been drawn forward into the machine. Fig. 12 is a detail section on line 12—12 in Fig. 11. Fig. 13 is a perspective of one of the blocks upon which the knives are mounted. Fig. 14 is a perspective of the wheel or head on which the said blocks and knives are mounted. Fig. 15 is a plan of the rear end of the machine, showing the gearing for driving and controlling the machine. Fig. 16 is a section on line 16—16 in Fig. 15. Fig. 17 is a detail sectional view of one of the rolls or gripping devices for holding the transfer in place. Fig. 18 is an enlarged end elevation of one of the devices for stopping the motion of the transfer. Fig. 19 is a section on line 19—19 in Fig. 18. Fig. 20 is an enlarged detail view of the joint in the arm which is engaged by the knife blocks to reverse the motion of the transfer after the top is cut off from the tubular fabric on the tapered mandrel. Fig. 21 is an enlarged detail section of the mounting for the arm that the revolving knife blocks engage to reverse the motion of the transfer. Fig. 22 is a perspective of the hollow swivel post shown in Fig. 21. Fig. 23 is a perspective of one of

the pins used for starting the machine. Fig. 24 is a perspective of the locking pin shown in Fig. 21. Fig. 25 is a detail sectional view of the two starting pins and the lever for operating them. Fig. 26 is an enlarged detail plan view of one of the starting connections. Fig. 27 is an enlarged detail view of a fragment of the fabric, showing position of the mandrel and the transfer. Fig. 10 28 is a perspective of one of the teeth or points for shifting the loops of yarn from the quills or points of the holder to the similar quills or points of the transfer. Fig. 29 is a detail view illustrating the manner in 15 which the fabric and the mandrel are supported. Fig. 30 is a diagrammatic plan view showing the position of the reversing lever just at the moment the fabric is being cut. Fig. 31 is an enlarged detail sectional view 20 of the transferring points and rings—that is to say, the points which transfer the loops of the fabric from the machine to the points or quills or the regular transfer rings. Fig. 32 is a side elevation of the mechanism 25 shown in Fig. 30.

As thus illustrated, my invention comprises a base or bed A upon which the various operative parts are mounted in suitably elevated positions. There are three 30 frames B, C and D provided respectively with rings b, c and d. Arranged concentrically within the said rings is the mandrel E, which mandrel is tapered toward its rear or outer end. These three rings are alike, or 35 substantially the same, and the description of one will suffice for all. In Fig. 2, the ring d is provided with a set of radially disposed arms d', which have plates d² adapted to engage between the ribs of the 40 knitted tubular fabric, and between the ribs e of the mandrel. In this way the tubular ribbed fabric is guided in a straight direction during its advancement lengthwise of the mandrel. These radial arms d' are provided with racks d³ which are engaged by the pinions d⁴. Another set of arms d⁵ are alternate with the other said set of arms, and are provided with rotatably mounted balls d⁶, which latter engage in the groove e' of 50 the mandrel. These arms have racks d⁷ engaged by pinions d⁸. It will be seen that all of said pinions are mounted in recesses in the ring d. These pinions are all connected by a chain d⁹, which latter is provided with a 55 handle d¹⁰. By operating this chain, one way or the other, the arms d' and d⁵ can be moved toward and away from the mandrel, whereby the fabric can be placed over the mandrel, and the mandrel and fabric then 60 engaged and supported by all of said arms. Rotary balls d⁶ keep the fabric under sufficient tension, while it moves forward. The said mandrel is preferably hollow and provided with a longitudinal passage e², which

passage is adapted to receive the rear end of 65 the top—that is to say, the severed portion of the fabric after the same has been cut off from the main portion of the tube of knitted fabric. With this arrangement the mandrel E is readily supported and released, and accurately centered and brought into alignment with the balance of the machine. The centering is done by operating the chains of their respective rings b, c and d. A frame F is supported at the other end of the base 70 75 or bed A, or near the center thereof.

The smooth horizontal rods G and H are secured rigidly in the frames D and F. The threaded rods I and J are also mounted in said frames D and F, but are adapted to 80 be rotated in bearings on said frames, whereby by the transfer is carried back and forth. The semi-circular frames K and L are movable, and adapted to travel back and forth on the said smooth and threaded rods, 85 when the threaded rods are rotated. The frame M is also semi-circular, but is rigid with the rods G and H, as shown in Fig. 3. The frame L is provided with beveled rolls or gripping devices l adapted to receive the 90 periphery or circumference of the transfer N. This transfer is circular, and has the usual set of quills or pins n. When inserted in the machine, it occupies the position shown in Fig. 5, being held in such position 95 by the yielding rolls l, which latter are pressed forward by the springs l' (see Fig. 17). The axis or center of the transfer is not in line with the upper and lower rolls l, but is to the right thereof, as shown in Fig. 100 5. Thus the transfer ring does not tend to fall out to the left. The transfer is placed in the machine by sidewise motion thereof, care being taken to have the points n exactly opposite the points m², and the operator 105 then presses his hand against the back of the transfer and moves it forward, the frame L being movable for this purpose. This causes the upper pin l² on the frame L to engage the spring-held pin m on the frame 110 M, with the result that the bent hook or pin m' carried by the pin m is caused to engage the pin m² on the lever m³. This lever is pivoted at m⁴ to the frame M, and is connected by a link m⁵ with the centrally pivoted lever m⁶, which latter lever is carried by the rock shaft m⁷ mounted in bearings on the frames M and F. This lever m⁶ is pivoted at m⁸ in the member m⁹, which latter is rigidly secured to the rock shaft m⁷, as 115 shown in Fig. 3. The upper end of the lever m⁶ engages a reciprocating pin m¹⁰, and the lower end of said lever engages a similar pin m¹¹, which pins are slidingly mounted in the ends of the member m⁹, (see Fig. 120 25). Thus, when the lever m⁶ is operated, as previously described, it causes the lever m⁹ to thrust the pin m¹⁰ outward, and this

pin is then struck by the roll i on the outer edge of a disk i' on the rotary threaded shaft I . This rocks the shaft m^7 , causing the spring m^{12} , which is secured at one end 5 to the ring M , to engage the notch m^{13} in the member m^9 , holding the latter in that position.

The member m^{14} is rigidly secured to the rock shaft m^7 , as shown in Fig. 6. It is 10 provided at its upper end with a threaded block m^{15} , adapted to engage the threaded shaft I , and at its lower end with a similar block m^{16} adapted to engage the threaded shaft J . It will be understood that one 15 shaft has a right hand thread, and the other shaft a left hand thread. When the shaft m^7 is rocked, in the manner just explained, the block m^{16} is caused to engage the threaded shaft J . The member m^{14} is connected by a link m^{17} with the frame K , as shown in Fig. 1, and by another link m^{18} with the sliding sleeve m^{19} , which latter has a rack m^{20} adapted to be engaged by the pinion m^{21} . (see Fig. 15), said pinion being freely 25 movable on a fixed stud. This causes the shaft J to move the member m^{14} toward the rear end of the machine, carrying the two frames K and L with it, and moving the sleeve m^{19} along in the same direction. 30 This sleeve, it will be seen, is on the rock shaft m^7 , and is supported in the frames F and O , as shown in Figs. 1 and 15. Thus the mere pressing forward of the transfer, after it is placed in the machine, serves to 35 automatically start the operation of the machine, as will hereinafter more fully appear.

The frame K , which slides on the rods G and H , is provided with a circular row 40 of radially and inwardly projecting teeth or points k . The frame M is provided with a circular row of outwardly diverging and forwardly projecting quills or points m^{22} , each quill or point having a groove adapted to receive one of the points k , (see Fig. 45 8). It will be seen that the quills or points m^{22} , have just sufficient dip or convergence to bring their ends between the ribs c on the mandrel. The stops m^{23} on the frame M are adapted to be engaged by the adjustable pins l^a to limit the motion of the frame L toward the frame M . The hook m^{24} is pivoted on the frame M , and provided with a hook-shaped forward end portion m^{25} adapted to engage the pin or roll 50 l^a on the frame L . This hook m^{24} holds the frame L stationary while the frame K moves forward, and until the loops are transferred to the points n . Then when the roll k' on the frame K engages the bevel m^{26} on the hook, the latter is released from the roll or pin l^a on the frame L , with the result that 55 the two frames move forward together, when the threaded rod J is rotated and engaged by the part m^{16} . The forward mo-

tion of the two frames in unison results 65 from the engagement of the points k with the shoulder n' on the transfer. In doing this, it will be seen that the points k pass from the grooves in the quills m^{22} to the grooves in the quills n . In order that the 70 points may follow said grooves, said points may have radial or endwise motion in their mounting, against suitable spring tension, as shown. The hook k^2 is pivoted on the frame K , and is provided with a hook-shaped forward end portion k^3 adapted to engage the roll or pin l^a on the frame L . This is the normal position of the parts; but when the two frames are moving forward together, then the roll or pin l^a engages the hook portion k^3 with which the said pivoted hook is provided, thus shortening the distance between the two frames K and L , so as to keep the points k in position to hold the loops on the points n . The hook 85 k^2 has a finger k^4 adapted to engage a roll or pin l^a on an arm k^6 , which latter is mounted on the frame M . When the frames move forward, the hook does not rise, the arrangement being such that the finger k^4 being pivoted to yield or swing in one direction can pass the roll or pin l^a without raising the hook; but when the frames come back, then the finger k^4 engages the roll or pin l^a , with the result that the hook is lifted 90 and the portion k^3 disengaged from the pin or roll l^a . In this way the frame L stops, while the frame K moves on until the points k are again in the position shown in Fig. 8.

It will be understood that the fabric is 100 drawn over the mandrel, and that the loops at the raw edge of the tubular fabric are placed, in any suitable manner, by hand, if necessary, upon the points or quills m^{22} . As will hereinafter more fully appear, the manipulation of the web or tube of fabric by hand is only necessary in putting the same on the machine, for after that the action is 105 entirely automatic until the web is used up and a new one is necessary. When the machine is started, in the manner described, the said loops are then shifted on to the quills n by the action of the points k . In other words, each point k engages a loop on 110 the edge of the fabric and transfers it from the quill m^{22} to the quill n . Thus the loops are shifted on to the quills of the transfer. The transfer then moves forward, together with frame K , pulling the fabric after 115 it, and when a sufficient length of fabric has been pulled forward, the motion is automatically stopped. This is accomplished by a device j on the rotary shaft J , which device is provided with pins j' which revolve around, and which strike the lower end of 120 the member m^{14} . This moves the rock shaft m^7 sufficiently to enable the spring m^{12} to 125 engage the middle notch m^{27} , holding the

threaded blocks on said member out of engagement with both of said threaded shafts. At this time the knife head P has advanced to the position shown in Fig. 8, by the forward motion of the sleeve p upon which it is mounted. It will be seen that this sleeve has a rack p' that is engaged by the pinion m^{21} , whereby the motion of the sleeve m^{19} in one direction is accompanied by the motion 10 of the sleeve p in the other direction. The said knife head P is not rigid with the sleeve p , but is carried on a shaft p^2 that rotates within the sleeve p , the sleeve and shaft, however, being held against relative endwise motion by ordinary collars or other like devices. The said sleeve carries adjacent to the knife head a set of tension rolls p^3 mounted on a spiral spring p^4 . It will be understood that the said knife head and the 20 said tension rolls are shown in Fig. 8 merely for convenience of illustration, and that in practice they never occupy this position at the time when the transfer is in the position shown in Fig. 8. When the transfer is in 25 this position, then the said knife head and tension rolls are at the other end of the machine, see Fig. 1; and vice versa, when the knife head and tension rolls are in the position shown in Fig. 8, then the transfer is at 30 the other end of the machine. The said knife head consists of a wheel p^5 provided with arms p^6 , to which are pivoted the blocks p^7 . These blocks are provided with slots p^8 for the adjustment of the knives p^9 , 35 which latter are secured thereon by bolts p^{10} . In their normal positions the knives are tangentially arranged, as shown in Fig. 11, and are held in position by the elastic band or spring p^{11} . This elastic band or spring extends around the knife head and engages the grooved rolls or bolt heads p^{12} , as shown in Fig. 12. When the knife is rotated, then the knives fly out, owing to centrifugal force, as shown in dotted lines in 45 Fig. 13. The ends of the knives engage the inner surface of the tubular fabric and cut quickly through the same, severing the portion of the fabric which is on the transfer from the portion which remains on the mandrel. While the transfer is moving forward, the portion of fabric thereon is supported by the tension rolls p^3 , and the latter in rotating, by reason of the forward motion of the fabric, place the spring p^4 50 under tension. As soon as the portion of fabric on the transfer is cut off, and as soon as the motion is reversed, then the rolls p^3 revolve under the tension of their spring, as they move back to the other end of the machine, and feed the end of the cut off portion of the fabric into the mouth of the hollow mandrel. This keeps the cut off portion from becoming entangled with the machinery, and during such backward move-

ment the loops are held on the transfer by 65 the points h .

The motion of the transfer is reversed as follows: When the knives are thrown out by centrifugal force, their blocks p^7 engage the roll Q on the end of the lever q , which latter is pivoted at q' upon the hollow swivel post q^2 , (see Figs. 21 and 22). At such time the said roll, of course, rests against the outside of the fabric. This lever has a jointed end portion q^3 which permits it to pass the frame 75 M, when it is swung around by the ring-like frame K striking it or moving away from it, and is also jointed at q^4 , whereby it is free to swing around in a horizontal plane, notwithstanding its connection with the upper 80 end of the link q^5 . This lever is swiveled on a post, as shown, because it must swing around when the frames and transfer come back, and must at such time extend longitudinally of the machine. When the knife 85 blocks engage the roll Q, the end of the lever q is depressed, and its notch q^6 is caused to engage the spring-pressed bolt or locking device q^7 , which latter is arranged in the hollow swivel post (see Fig. 21). This 90 raises the link q^5 , and this link in turn raises the link q^8 through the medium of bell crank and link connections q^9 , shown more clearly in Fig. 1. This link q^8 operates the lever m^6 , previously described, causing it to eject 95 the pin m^{11} from the lower end of the lever m^9 . When this is done, the said pin m^{11} is engaged by the roll R on the disk r of the rotary shaft J, (see Fig. 3). In this way the member m^9 is tilted and the shaft m^7 rocked 100 until the block m^{15} is caused to engage the threaded shaft I. The parts are held in this position by engagement of the spring m^{12} with the notch m^{28} on the member m^9 , (see Fig. 3). Thus, the motion of the machine is 105 reversed, and the transfer caused to travel back toward the mandrel, while the knives and tension roll are caused to travel in the other direction. When the member m^{14} reaches the position shown substantially in 110 Fig. 1, then it is kicked out of engagement with the shaft I by a device S, which device is similar to the device j , previously described. Thus the spring m^{12} is returned to the middle notch m^{27} and the machine is at 115 a stand still with the cut off portion of the fabric resting inside of the mandrel. At the time that the knives cut off or sever a portion of the fabric from the main portion thereof, the new or fresh loops formed 120 thereby on the raw edge of the fabric spring into position on the points m^{22} , or may be placed thereon by hand, if any of them fail to catch, thus putting them in readiness to be shifted to the transfer. The fabric is, of 125 course, stretched on the mandrel, and when it springs back, after being cut, the points or quills m^{22} , which depress the fabric into

the grooves or channels between the ribs e , find their way into the new loops on the raw edge of the fabric. This, of course, is due to the fact that the fabric is first forced 5 outward by the knives, so that the quills m^{22} are inserted in the new loops for about one-eighth of an inch; and then when the fabric springs back—that is, when the fabric springs longitudinally toward the left in 10 Fig. 8—the said points or quills m^{22} are then thrust one-eighth of an inch deeper in the loops; the points k , when they return, will then move the said loops still farther upon the said quills m^{22} and then glide over to a 15 point behind them. When the frames and transfer again move forward, the lever q again swings around so that the roll Q is against the web, and then in position to be struck by the blocks q^1 the next time the 20 knives fly out.

It will be seen that the sleeve p is held by a spline or pin T against rotation with the shaft p^2 , (see Fig. 16). The gear wheel U rotates loosely upon the sleeve p , and is 25 provided with two sets of teeth, one adapted to engage the pinion u that drives the shaft I , and to also engage the pinion u' that rotates the shaft J . The other set of teeth are beveled to engage a bevel pinion u^2 on 30 the shaft of the fast and loose pulleys V . This is the drive shaft and it is provided with a smooth bevel friction wheel v adapted to engage a similar wheel v' on the shaft p . This friction wheel v' is mounted on a 35 sleeve v^2 that is splined on the shaft p^2 , and which has a slight forward and back movement in the bearing O (see Fig. 15). A spring pressed arm v^3 , operated by a hand lever v^4 (see Fig. 1) holds the wheel v' normally out of engagement with the wheel v , 40 whereby the knives do not revolve until the collar W on the shaft p^2 engages the end of the sleeve of the wheel v' , thus crowding the latter into engagement with the wheel v . 45 This occurs at about the time the knives reach the limit of their movement toward the mandrel, and at a time when it is proper for the cutting operation to take place. Thus the knives do not revolve while the 50 fabric is being drawn forward by the transfer.

When the transfer moves back toward the mandrel, and when the frames or rings K and L of the machine stop automatically, 55 then the transfer is removed. This is done by hand by removing it sidewise from the machine, and the cut-off portion of the fabric comes off with it. This cut-off portion of the fabric is destined to become the top of a knitted sock or stocking, or of a similar knitted article. Heretofore these tops have been placed on the transfers by hand or by mechanism requiring a stationary transfer, as previously explained. This was laborious

and expensive, as it took a great deal of time 65 to place the tiny loops of yarn, especially those of silk or other finely knit hosiery, on the quills or transfers; and the mechanism proposed for the work involved the placing of the loops on the transfer after the fabric 70 was stretched, instead of before, which latter gives the best results. Now, however, and with my automatic machine, as herein disclosed, each top is automatically placed in position on a transfer, which latter is then 75 moved backward to stretch out the fabric. After this, the transfer can be used for transferring the top to a suitable knitting machine, in the regular and well understood manner. Thus time and labor are saved and 80 the cost of production considerably reduced.

With further reference to the mode of operation, particularly the cutting of the fabric and the manner in which the loops on the raw edge of the fabric are replaced on the 85 points m^{22} , it will be seen that the semi-circular ring or frame K , has a preliminary movement toward the transfer ring N , to enable the radially projecting fingers k to transfer the loops on the stationary quills N to the quills n of the transfer ring N . At the time that said loops are positively transferred, the sliding frames K and L move in unison toward the right of the machine, and away from the tapering mandrel 95 E . As the frame K moves toward the right of the machine, obviously the fabric follows with it, and forms a taut, hollow cylinder, from the end of the mandrel to the transfer ring. It will also be seen that as the frame 100 K retreats, the reversing lever q , which normally engages the edge of the frame K , (as is shown in dotted lines in Fig. 30), will follow said frame, through the action of the spiral spring q^8 (see Fig. 21) one extremity 105 of which is connected to the supporting member, and the other extremity to the swiveling post q^2 . Thus it will be seen, that when the frame K , is in the position as shown in Fig. 8 the spring q^8 is under tension, and has a tendency to bring the arm q , in a central position, and in a position adjacent to the cutting off mechanism, (as shown in full line position in Fig. 30). When the frames K , and H , have traveled to their farthest position to the right of the machine the reversing lever q is in a position as shown in (Fig. 30) and the flexible member q^3 carrying the roller Q , is resting against the periphery of the taut cylinder of fabric. 110 From this it will be seen that as centrifugal force throws open the cutting knives p^9 , and the fabric carried by the transfer ring is severed from the main body of fabric, the taut cylinder becomes, yielding or open, and 115 the flexible member q^3 snaps into the path of, and adjacent to the blocks p^7 . It will also be seen that the fabric is cut before the

reversing lever q , can fall in a position to be operated upon by the blocks p^7 . The points m^{22} being seated in between the ribs 3 of the mandrel E, causes them to bear into the fabric, and the fabric being stretched about the mandrel E, and also being pulled out by the transfer ring, causing the loops to be held in an open position, has a tendency when cut off, to spring back, and the points m^{22} being constantly in the path of the loops, said loops in their back motion, ride free and easy upon the points m^{22} . The tube of fabric, remaining upon the mandrel, if necessary can be given a slight pull toward the small end of the mandrel, causing the loops to ride farther up on the points m^{22} . When the transfer ring moves toward the right of the machine, the fabric causes the rolls p^3 to rotate and winds up the spring p^4 , which puts a tension on said rollers. When the fabric is cut, the rollers p^4 support the fabric that is cut, and held at the other end by the transfer ring, and when the transfer ring moves to its initial position, the fact that the rollers p^3 are under tension and are rotating in the direction of travel of the transfer ring, causes the fabric to be fed toward the mandrel, and not buckle or kink in the center, and the rolls also act as a support till the transfer ring has reached the end of its movement. Thus it will be seen that when cutting the fabric, the knives from the interior will force the tube about one-quarter inch outward, while the quills m^{22} by reason of their spiral springs, will find their way into the ribs of the new loops by about one-eighth of an inch. In other words, the loops will replace themselves on the quills m^{22} from the interior outward. When the fabric is cut, the tube on the mandrel E will at the same moment spring backward about one-quarter of an inch, while the quills m^{22} will for the second time find their way about one-eighth of an inch deeper into the new loops. The main work in reinstating the loops on the raw edge of the fabric is done by the fingers k in two different ways: Firstly:—When the fingers k come back with their ring K, they will arrive exactly in the open quills m^{22} , and push or thrust the already (by one-eighth inch) self-reinstated loops entirely (one-half inch) and farther up on the quills; the fingers k will then glide over the loops and by means of their spiral spring they will be placed about at the bottom of the loops within the quills m^{22} . Secondly:—The same fingers k will push the finished reinstated loops down from their quills m^{22} , upward upon the set-in transfer points n ,—that is to say, the smaller quills n on transfer ring n^1 will be thrust into the quills m^{22} by one-eighth inch, and when the machine is put in motion, the ring K will by means of its fingers k slide the reinstated loops from

the quills m^{22} upon the thrust-in transfer point n . I do not, however, limit myself to the exact construction or mode of operation shown and described.

In the claims, and by the terms "transfer" and "receiving means," it will be understood that the ring N is the element mentioned therein, this being the removable means for conveying fabric to a knitting machine. It will be understood that the knife operates, or may operate, quite close to the points m^{22} and while the latter are in engagement with the loops at the edge of the cut, depending upon the character of the fabric.

What I claim as my invention is:

1. In a machine of the character disclosed, a set of points operative to deliver the loops at the edge of the end of the fabric to the quills of a transfer ring, means for causing the fabric to be stretched and drawn out a distance by movement of the transfer away from the receiving position thereof, and means for then cutting off the stretched out fabric, leaving the same on the transfer ring.

2. In a machine of the character disclosed, the combination of means for holding a removable transfer, a holder for the fabric, tapered away from the transfer, means for removing the raw edge of the end of the fabric from the holder and placing the same on the transfer, means to move the transfer backward with the uncut fabric, and means to then cut off the fabric.

3. In a machine of the character disclosed, the combination of traveling means for holding a transfer, means for placing the loops of the fabric on said transfer, and means for starting the machine by moving the transfer slightly in one direction of travel thereof.

4. In a machine for the purpose described, a removable transfer ring, means for holding the transfer ring in position, a mandrel for holding the tubular fabric tapered away from said ring, mechanism for carrying the end portion of the fabric to the transfer ring, and means for moving said mechanism and transfer ring to stretch the fabric.

5. In a machine for running-on knitted web, the combination with a support for the web, of means for engaging the stitches of the web, means for moving the stitch engaging means and the web longitudinally of said support, a cutting knife for said web, disposed within the web, means for moving the knife into and out of cutting engagement with the web, and means for carrying said knife around the web.

6. In a machine for running-on knitted web, the combination of a support for the web, means for moving the web over said support, a cutting knife for the web, dis-

- posed within the web, a knife carrier rotatable around the axis of the web support, and a knife-mount pivoted upon said carrier, within the web, and movable in a plane parallel with the face of the same for swinging the knife into and out of cutting relation with the web.
7. In a machine for running-on knitted web, the combination of a support for the web, means for moving the web over said support, a cutting knife for the web, disposed within the web, a rotatable knife-carrier upon which said cutting knife is mounted so as to move into and out of cutting relation with the web, a spring for normally holding the knife out of such cutting relation, disposed within the web, means acting in opposition to the spring for moving the knife into cutting relation with the web, and means for retaining the knife in such cutting relation.
8. A transfer machine provided with a knife for cutting the web in lengths, disposed within the web, and means for operating said knife.
9. In a machine for running-on knitted web, the combination, in operative relation to one another, of means for receiving the stitches of the web, means for engaging said stitches and transferring them to said receiver, means for cutting off a length of the web, and means for causing said length to move back toward the body of the web, after being cut off, in bringing the receiving means into normal position.
10. In a machine for running-on knitted web, the combination, in operative relation to one another, of means for receiving the stitches of the knitted web, means for engaging said stitches, stretching or expanding the web, and then applying the stitches to the receiver, means for cutting off a length of the web, and means for causing said length to move back toward the body of the web, after being cut off, in bringing the receiving means into normal position.
11. In a machine for running-on knitted web, the combination, in operative relation to one another, of means for receiving the stitches, means for engaging said stitches and transferring them to the receiving means, means for moving the latter into and out of operative relation to said transferring means, means for cutting off a length of the web, and means for causing said length to move back toward the body of the web, after being cut off, in bringing the receiving means into normal position.
12. A machine for running-on knitted web, having means for engaging the stitches to be transferred and drawing the web forward through the medium of such engaging means, means for cutting off a length of the web, and means for causing said length to move back toward the body of the web,
- after being cut off, in bringing the engaging means into normal position.
13. A machine for running-on knitted web, having means for engaging the stitches to be transferred, expanding the web, and drawing the same forward through the medium of said engaging means, means for cutting off a length of the web, and means for causing said length to move back toward the body of the web, after being cut off, in bringing the engaging means into normal position.
14. A machine for running-on knitted web, having means for engaging the stitches to be transferred and drawing the web forward through the medium of such engaging means, means for severing the portion of the web thus drawn forward from the remaining portion, and means for then causing said engaging means and severed portion to travel backward toward the other portion of the web, in bringing the engaging means into normal position.
15. In a machine for running-on knitted web, the combination, in operative relation to one another, of means for receiving the stitches to be transferred, comprising a removable and reciprocating transfer ring, means for engaging said stitches and expanding the web to bring the stitches into a plane substantially at right angles to their position in the unexpanded web, and means for transferring the stitches to the receiving means, movable forward and back therewith.
16. In a machine for running-on knitted web, the combination, in operative relation to one another, of a removable receiver having members for receiving the stitches to be transferred to another machine, means for simultaneously engaging the entire series of stitches to be transferred and adjusting them into position for transfer to the receiving members, means for simultaneously removing the entire series of stitches from the transfer members to the receiving members, and automatic means whereby said receiver moves in opposite directions to the full extent of its motion with the web thereon.
17. In a machine for running-on knitted work, the combination with a support for the web, of removable means for engaging the stitches of the web, means for moving the stitch engaging means and the web longitudinally of said support, a cutting knife for said web, means for moving the knife into and out of cutting engagement with the web, means for carrying said knife around the web, and automatic means whereby the severed portion of the web is carried bodily backward toward said support after being cut off, to permit removal thereof, in bringing the removable means into normal position.
18. In a machine for running-on knitted

web, the combination of a support for the web, means for moving the web over said support, a cutting knife for the web, a knife carrier rotatable around the axis of the web support, a knife-mount pivoted upon said carrier and movable in a plane parallel with the face of the same, for swinging the knife into and out of cutting relation with the web, and automatic means whereby the severed portion of the web is carried bodily backward toward said support, after being cut off, in bringing the web-moving means into normal position.

19. In a machine for running-on knitted web, the combination of a support for the web, means for moving the web over said support, a cutting knife for the web, a rotatable knife-carrier upon which said cutting knife is mounted so as to move into and out of cutting relation with the web, a spring for normally holding the knife out of such cutting relation, means acting in opposition to the spring for moving the knife into cutting relation with the web, means for retaining the knife in such cutting relation, and automatic means whereby the severed portion of the web is carried bodily backward toward said support after being cut off, in bringing the web-moving means into normal position.

20. In a machine for running-on knitted web, the combination of stitch-engaging and removable transfer devices, a carriage therefor, means for imparting forward and backward movement to said carriage, automatic means for effecting reversal in the direction of movement when the carriage is at the forward termination of its travel, before the removal of said devices, and means for cutting off a portion of the web, before such reversal, the severed portion being carried bodily backward by the return movement of the carriage to normal position, in bringing the transfer device into normal position.

21. In a machine for running-on knitted web, the combination of stitch-engaging and removable transfer devices, a carriage therefor, means for imparting forward and backward movement to said carriage, automatic means for effecting reversal in the direction of movement when the carriage is at the rearward termination of its travel, and means for cutting off a portion of the web, the severed portion being carried bodily backward by the return movement of the carriage, in bringing the transfer device into normal position.

22. In a machine for running-on knitted web, the combination of removable means for receiving the stitches of the knitted web, movable in opposite directions with the web thereon, to first stretch the web and then return with the same to a position of rest between the limits of said movement, and means for engaging said stitches and apply-

ing them to the receiver, one of said means being movable with respect to the other.

23. In a machine for running-on knitted web, the combination of reciprocating means for receiving the stitches to be transferred, movable in opposite directions with the web thereon, to first stretch the web and then return with the same to a position of rest between the limits of said movement, and reciprocating means for engaging said stitches and applying them to the receiving means whereby when the stitch engaging devices are retracted the stitches will remain upon the receiving devices.

24. In a machine of the character disclosed, the combination of means for holding the fabric, means for holding a removable transfer, movable back and forth in a straight line, mechanism for placing the loops at the end of the fabric on the transfer, movable back and forth therewith, and means for serving the fabric a distance from said end.

25. In a machine of the character disclosed, a removable transfer, means for supporting the fabric, a holder having quills for securing the loops at the raw edge of the end of the fabric, preparatory to placing the same on the transfer, means for causing the loops to engage said transfer, and means for moving the transfer to stretch out the fabric.

26. In a machine of the character disclosed, the combination of means for holding the removable transfer, means for first placing the loops of the fabric thereon, means for then measuring off a length of said fabric, by predetermined motion of the transfer, and means for finally cutting off such length, leaving the same on the transfer.

27. In a machine of the character disclosed, means for holding a removable transfer, means for automatically moving the transfer back and forth, whereby the transfer reciprocates in a straight line, means whereby the transfer receives a web at one end of its path of travel, and means for then causing the transfer and web to move in the opposite direction.

28. In a machine for loading transfers of the character disclosed, the combination of a mandrel for the tubular fabric, a holder for the fabric, a removable transfer, means for shifting the loops of the fabric from the holder to the quills of the transfer, mechanism for moving said means and the transfer back and forth to receive and stretch the fabric, and means for automatically cutting off the fabric when the transfer reaches the end of its forward stroke.

29. A machine for loading transfers, comprising movable means for holding the transfer ring, means for holding the fabric, means for placing the loops of the fabric on

the points or quills of the transfer ring and movable therewith, means for moving the transfer ring to feed the fabric forward, causing the same to be stretched, and automatic means for then severing the fabric between the said transfer ring and the means for holding the same.

30. In a mechanism for the purpose described, a traveling transfer ring, means for holding the transfer ring in position, means for holding the fabric, mechanism movable toward the transfer ring to carry the fabric onto the points thereof, and also movable therewith, and means for moving the said 10 ring back and forth, whereby said ring has movement to stretch the fabric.

31. A machine for the purpose described, a set of members for holding the end portion of the tubular fabric, a removable and 20 movable transfer, a set of points operative to move the end portion of the fabric from the said members to the said transfer, and means for operating said points and transfer together to stretch the fabric.

25. 32. In a machine for the purpose described, a mandrel, a removable transfer, and means for stretching a length of the tubular fabric between the transfer and the end of the mandrel, by motion of the transfer, whereby the fabric is fed endwise from the end of the mandrel, and means for bringing the transfer to rest at a point between the limits of its motion.

33. In a machine for running-on knitted 35 web, the combination, in operative relation to one another, of means for receiving the stitches, mounted to move back and forth in the longitudinal direction of the web, removable from the machine with a portion of 40 the web thereon, means for engaging said stitches and transferring them to the receiving means, adapted also to travel back and forth therewith, and means for moving the receiving means into operative relation to 45 said transferring means.

34. A machine for running-on knitted web, having means for engaging the stitches to be transferred and drawing the web forward through the medium of such engaging 50 means, removable transfer means for receiving the stitches and then drawing the web forward, arranged also to travel back and forth with said engaging means, and means for bringing the said receiving means to 55 rest before reaching the receiving position thereof.

35. A machine for running-on knitted web, having means for engaging the stitches to be transferred, expanding the web, and 60 drawing the same forward through the medium of said engaging means, means for receiving the stitches and then drawing the web forward, removable from the machine with a portion of the web thereon, and 65 means for bringing the said receiving means

to rest before reaching the receiving position thereof.

36. A machine for running-on knitted web, having means for engaging the stitches to be transferred, and drawing the web forward through the medium of such engaging means, means for receiving the stitches and then drawing the web forward, and means for severing the portion of the web thus drawn forward from the remaining portion, 70 disposed inside of the web.

37. In a machine for running-on knitted web, the combination, in operative relation to one another, of means for receiving the stitches to be transferred, removable from 80 the machine with a portion of the web thereon, means for engaging said stitches and expanding the web to bring the stitches into a plane substantially at right angles to their position in the unexpanded web, means 85 for transferring the stitches to the receiving means, and mechanism for moving the receiving means to stretch out the required length of web.

38. In a machine for running-on knitted web, the combination, in operative relation to one another, of a receiver which is removable from the machine with a portion of the web thereon, having members for receiving the stitches to be transferred, means for 95 simultaneously engaging the entire series of stitches to be transferred and adjusting them into position for transfer to the receiving members, devices for simultaneously removing the entire series of stitches from the 100 transfer members to the receiving members, and means for operating the latter and said devices to stretch out the required length of web.

39. In a machine for running-on knitted web, the combination of stitch-engaging and transfer devices, said devices including a transfer ring, a carriage therefor, means for imparting forward and backward movement to said carriage, tracks for the carriage, and automatic means for effecting reversal in the direction of movement when the carriage is at the forward termination of its travel, said ring being removable with a portion of the web thereon, and means for automatically 110 stopping the movement of said ring.

40. In a machine for running-on knitted web, the combination of stitch-engaging and transfer devices, said devices including a transfer ring, a carriage therefor, means for imparting forward and backward movement to said carriage, and automatic means for disengaging said moving means from the carriage at both the forward and rearward termination of its travel, said ring being 120 removable with a portion of the web thereon, together with means for automatically 125 stopping the movement of said ring.

41. In a machine for running-on knitted web, the combination of means for receiv- 130

- ing the stitches of the knitted web, mounted to move back and forth to receive and stretch the web, and means for engaging said stitches and applying them to the receiving means, movable back and forth therewith, one of said means being movable with respect to the other, and said receiving means being removable from the machine with a portion of the web thereon.
- 10 42. In a machine for running-on knitted web, the combination of means for receiving the stitches to be transferred, mounted to move back and forth to receive and stretch the web, and means for engaging said
- 15 stitches and applying them to the receiving means, movable back and forth therewith, and said receiving means being removable

from the machine with a portion of the web thereon after returning to receiving position. 20

43. A transfer machine provided with a mandrel for supporting and gradually expanding the tubular web, tapered in the direction of the receiving end thereof, made hollow to receive the severed portion of the 25 web, and means for feeding the reversed portion back into said mandrel.

Signed by me at St. Joseph, Michigan,
this 15th day of March, 1909.

EDWARD MASLICH.
